(57) **CLAIM**

The ornamental design for a razor cartridge shaving aid assembly, as shown and described.

DESCRIPTION

FIG. 1 is top view of a first embodiment of an ornamental design for a razor cartridge shaving aid assembly according to the present invention;

FIG. 2 is a bottom view thereof;

FIG. 3 is a right view thereof;

FIG. 4 is a left side view thereof;

FIG. 5 is a front side view thereof;

FIG. 6 is a bottom view thereof;

FIG. 7 is a front perspective view thereof;

FIG. 8 is top elevational view of the ornamental design of the first embodiment shown with a shaver environment;

FIG. 9 is a bottom elevational view thereof;

FIG. 10 is a right view thereof;

FIG. 11 is a left view thereof;

FIG. 12 is a back view thereof;

FIG. 13 is a front view thereof; and,

FIG. 14 is a back perspective thereof.

All portions shown in broken lines are environmental and illustrative only and form no part of the claimed design.

1 Claim, 14 Drawing Sheets
